UNITED STATES PATENT OFFICE.

GEORGE SHATTUCK GATES, OF ATHOL, MASSACHUSETTS.

HARNESS-TRACE.

SPECIFICATION forming part of Letters Patent No. 289,403, dated December 4, 1883.

Application filed September 5, 1883. (No model.)

To all whom it may concern:

Be it known that I, GEORGE SHATTUCK GATES, of Athol, in the county of Worcester, of the Commonwealth of Massachusetts, have 5 invented a new and useful Improvement in Harness-Traces; and I do hereby declare the same to be described in the following specification, and represented in the accompanying drawings, of which—

10 Figures 1 and 2 are longitudinal sections, Fig. 3, a transverse section, and Fig. 4 a side view, of the whiffletree end portion of a trace provided with my invention, the nature of which is defined in the claim hereinafter presented. Fig. 5 is a view of the wire-cord re-enforced; and Fig. 6 is a perspective view of the auxiliary re-enforce, to be described.

When a harness-trace breaks, the separation is generally crosswise of it at its rearmost or 20 whiffletree eye or slot. My invention is to there strengthen it, so as to prevent the leather about the eye from being cracked or torn apart while the trace may be in use. To this end I insert between the two straps *ab*, of which the 25 trace is usually composed, and to surround the hitching eye or slot *c*, formed through them, a closed loop or elongated ring of wire cord, and I extend through such loop or ring, at its upper part, and also through the two straps *ab*, 30 at a point some distance above the said slot, a rivet, *A*, having a flat head, *d*. The shank of the rivet goes through a washer, *e*, and is upset thereon. The two straps are subsequently to be stitched together in the ordinary 35 way. Previous, however, to so connecting them, there is to be extended wholly or partially around the metallic cord re-enforce, at its lower end, a metallic plate or auxiliary re-enforce, *f*, such being as represented, and for 40 the purpose of shielding the cord re-enforce from wear in case of the leather of the eye be-

coming cut or worn through by the whiffletree connection or button. When the wire is in place, the re-enforce *f* is between the pieces of leather and out of sight. It only comes into 45 play after the leather at the rear of the eye has been worn, and then serves to keep the wire from being worn.

From the above it will be seen that the metallic cord re-enforce is supported by the rivet 50 which keeps the wire from being pulled backward through the trace, and with such serves to relieve from strain the parts flanking the eye or slot.

The metallic cord re-enforce is made of wires 55 braided or twisted together, and of a consequence is of a sufficient flexibility to enable the trace to be buttoned on or unbuttoned from a whiffletree, as occasion may require.

I am aware that harness has been provided 60 with a wire cord running through it and around the whiffletree-eye; also, that the whiffletree-eye of a trace has been strengthened by a re-enforcing plate. In the present device the wire is only used at the eye, the remainder of the harness being as usual. The piece 65 of wire cord surrounds the eye and is held in place by the rivet, the re-enforcing plate, and the stitching.

What I claim is—

A harness-trace having the whiffletree-eye *c*, in combination with a closed loop of wire 70 cord held in the trace and surrounding the eye *c*, the rivet *A* in front of the eye *c*, and passing within the wire loop, and the re-enforce *f* at 75 the rear of the eye *c*, surrounding the wire and between the pieces of leather, as set forth.

GEORGE SHATTUCK GATES.
